UNITED STATES PATENT OFFICE.

JOHN E. ZOOK, OF KANSAS CITY, MISSOURI.

WINDOW WASHER.

Application filed May 23, 1927. Serial No. 193,503.

My invention relates to window washing machines and one object is to provide a portable machine of this character whereby windows may be washed without requiring the operator to stand upon the outside of the window sill where he would be more or less in danger of falling and becoming seriously injured.

A further object is to provide a substantial and efficient machine of this character which can be manufactured and marketed at a reasonable price.

Other objects will hereinafter appear and in order that the invention may be fully understood, reference will now be had to the accompanying drawings, in which:

Fig. 1 is a broken vertical section of a window with the machine in position for washing the glass in the upper sash.

Fig. 2 is a plan view of the machine.

Fig. 3 is a front elevation of the machine.

Fig. 4 is a section on line 4—4 of Fig. 2.

Fig. 5 is a broken cross section on line 5 of Fig. 1 showing means for securing the front portion of the machine to a window sill.

Fig. 6 is a detail plan view of a mop employed in carrying out the invention.

Fig. 7 is an end elevation of the machine equipped with an electric motor for driving the mop actuating mechanism.

In carrying out the invention I employ a telescopic frame 2 consisting of a primary section 4 and a secondary section 6 which are slidably connected so that the frame may be extended or contracted to fit window sills of different widths. The primary section 4 is provided at its lower rear portion with one or more depending brackets 3 having a like number of set screws 5 adapted to engage the rear ledge A of the window sill B. The secondary section 6 is provided with a hook 7 adapted to engage under the front ledge C of the window sill B and thus coact with the set screws 5 in firmly securing the frame 2 in position.

The hook 7 is secured to a block 9 which is provided with grooves 11 which receive the lower flanges on the lower angle bars of the secondary frame, as shown by Fig. 5. The foregoing arrangement permits the hook 7 and the block 9 to be slid backwardly and forwardly upon the secondary frame section 6 to accommodate window sills of different

widths so that it will not be necessary to extend the telescopic frame 2 except to accommodate window sills of usual width.

The forward end of the secondary frame section 6 is equipped with a fixed segmental plate 8, against which a moveable segmental 60 plate 10 is held by guides 12 secured to said fixed plate 8. The segmental plate 10 is rockable about the axis of a drive shaft 13 extending longitudinally of the frame 2 and 65 journaled in bearings 14 and 16 at the rear and front portions of the primary and secondary sections 4 and 6, respectively. The drive shaft 13 is provided at its rear end with a crank 20 whereby it may be manually 70 rotated and is provided at its forward end with a fixedly mounted bevel gear 21 which intermeshes with a bevel gear 22 fixedly mounted upon a counter-shaft 24 journaled in bearings 26 mounted upon the rockable 75 plate 10. The countershaft 24 is provided with a fixedly mounted cog wheel 28 which intermeshes with a rack 30 fixed upon a bar 31 which is reciprocably mounted in a guide 32 carried by a yoke 34 rockably 80 mounted upon the countershaft 24.

The bar 31 is provided at its upper end with a mop, or other suitable window cleaning device 35 which includes a back plate 36 and a clevis 38, which latter is connected to 85 the former by a pivot 39 and connected to the upper end of the bar 31 by a pivot 40.

In practice the frame 2 is fitted to the window sill B either by adjusting the hook 7 and the block 9 forwardly or backwardly 90 or by adjusting the secondary frame section 6 forwardly or backwardly. If the secondary section 6 is adjusted the drive shaft 13 moves backwardly or forwardly therewith and accordingly slides in the bearing 14. 95 After the frame 2 has been adjusted and secured to the window sill B the bar 31 is grasped with one hand to guide the mop over the outer glass D, while the crank 20 is rotated in reverse directions with the 100 other hand to effect up and down movement of the mop to the top and bottom of said glass D. During the foregoing operation the mop can be moved in any direction over the window glass D due to the rockable 105 movement of the segmental plate 10, the yoke 34, and the pivots 39 and 40.

When the machine is equipped with an electric motor 40^a as shown by Fig. 7, it will not be necessary to operate the crank 20 by 110

hand, as said motor 40^a, through the intermediary of the train of gears 46, will actuate the drive shaft 13^a, which latter is provided with a spline 48 so that it may slide 5 through the large gear 50 of the train 46 and at the same time be driven by said large gear. The motor 40^a is preferably of the reversible type so that when the mop reaches the end of an upward stroke said motor may 10 be reversed to effect a down stroke of said mop, or any well known form of reversible gearing may be associated with the train 46 for that purpose.

From the foregoing description it will be 15 apparent that I have provided a window washing machine embodying the advantages above pointed out, and while I have shown a preferred embodiment of the invention I reserve all rights to such changes and modi-

fications as properly fall within the spirit 20 and scope of the invention as claimed.

Having thus described my invention, what I claim and desire to secure by Letters Patent, is:

In a machine of the character described, 25 a frame adapted to be secured to a window sill, a window cleaning device, a rack, a guide for said rack, a yoke to which said guide is fixed, a plate rockably mounted at the forward portion of the frame and provided with bearings in which a shaft is journaled, a gear wheel mounted upon said shaft for driving the rack, intermeshing bevel gears for driving said shaft, and a drive shaft mounted in the frame and upon 30 which one of said bevel gears is mounted.

In testimony whereof I affix my signature.
JOHN E. ZOOK.
